UNITED STATES PATENT OFFICE

1,934,581

COMBINATION INSULATOR AND MULTIPLE CONNECTER

Robert S. Bach, Ventura, Calif.

Application September 7, 1932. Serial No. 632,055

1 Claim. (Cl. 173—28)

This invention is a combined insulator and multiple connector for supporting and connecting conductors such as are used for supplying consumers with electric service from electric lines, and in accordance with the present invention an apparatus of the above mentioned character is provided which can be readily and easily applied to the pin of a cross arm or other suitable support, consists of relatively few parts and will be found thoroughly efficient for the purpose designed.

The invention together with its numerous objects and advantages will be best understood from a study of the following description taken in connection with the accompanying drawings wherein:

Figure 1 is an elevational view of the invention complete.

Figure 2 is a longitudinal sectional view therethrough.

Figure 3 is a transverse sectional view through a connector or distributor bolt, and cap therefor.

Figure 4 is a perspective view of the connector or distributor bolt or rod.

Figure 5 is a perspective view of an anchoring plug or sleeve.

Figure 6 is a longitudinal sectional view through the connector bolt or rod and cap.

Figure 7 is a perspective view of the insulator and

Figure 8 is a bottom plan view of the connector rod, and cap shown in Figure 6.

With reference more in detail to the drawings it will be seen that 5 designates a pin usually provided on a cross arm or other suitable support and having a threaded portion 6.

In accordance with the present invention there is provided an insulator 7 which may be formed of any insulating material, but in the present instance is formed of porcelain and comprises a body of the shape shown having an internally threaded portion 8 to receive the threaded portion 6 of the pin 5 as shown. At its upper end the body of the insulator 7 is provided with a circular recess 9 the wall of which is provided with an internal annular groove 10 as and for the purpose to be hereinafter made manifest.

What may be termed a distributor or connector comprises a pole of brass and of a suitable length. The pole 11 has a grooved end portion 12 adapted for disposition in recess 9 and said end portion is anchored within the recess through the means of an anchoring plug or collar c which includes a substantially cylindrical internally ribbed body fitting within the recess 9 with the

internal ribs 11a fitting in the grooves 12. The body of the plug c is also provided with an external rib or flange 13 engaged within the internal groove 10 as shown in Figure 2. Preferably the plug c is formed of sulphur, lead or insulator cement or other suitable material, which in molten form is poured into the recess 9 subsequent to the placing of the grooved end 12 of the pole 11 within said recess.

The connector pole 11 is provided with a longitudinal series of vertically spaced openings 14 extending transversely therethrough for accommodating the ends of a plurality of wires or conductors 15, alternate wires 15 extending from relatively opposite sides of the pole. The pole is also provided on relatively opposite sides thereof with threaded apertures 16 opening into the openings 15 and accommodating binding screws 17. The uppermost hole 14 is of relatively large diameter for receiving one end of the line wire 18, and as shown in Figures 1 and 6 instead of using screws 17 for electrically connecting wire 18 and the uppermost one of the wires or conductors 15 with the pole 11 blind set screws such as indicated at 19 may be used for this purpose. As will be noted the blind set screws 19 have their heads provided with hexagonal recesses for the application of a suitable tool thereto for tightening the screws 19 or loosening them as found desirable.

For the connector pole 11 there is provided a cap 20 formed of suitable insulating material, preferably "bakelite". The cap 20 comprises a body portion having an axial opening therethrough for accommodating the pole 11 and also having radial openings 21 for accommodating the wires 15, 18. It will be noted that the openings 21 are so arranged that when the cap 20 is fitted on the pole 11 alternate openings 21 will be closed at one end. (See Fig. 2.) If desired plugs of cork or other suitable material (not shown) may be passed through the openings 21 for closing the open end of the openings 14. The use of such plugs however will not be necessary unless the combined insulator and distributor is being used where atmospheric conditions are such as to cause brass and copper corrosion, for example when the device is used where atmospheric conditions are such that there is almost a continuous "fog belt".

It will be also noted that the body of the cap 20 at its lower end is circumferentially enlarged, and is provided with a circular recess 22, receiving the upper end of the body of the insulator 7.

As suggested in Figure 1 one or more of the

wires 15 can be looped about the body of the insulator 7, the body of said insulator being provided with an external annular groove 23 for this purpose.

5 From the foregoing description taken in connection with the accompanying drawings it is thought that the construction, operation and advantages of this invention will be readily understood by those skilled in the art to which the invention appertains.

10 Having thus described my invention, what I claim as new is:

15 In combination, an insulator comprising a body provided with a threaded socket having internal threads, a connector pole secured at one end

to said insulator body, and provided with a series of relatively spaced transverse wire receiving openings extending therethrough, and being also provided with additional threaded openings adjacent said wire receiving openings, binding screws threadedly engaged with said threaded openings, an insulation cap covering said pole and provided with radial apertures aligning with the first named openings in said pole for accommodating the wires, and said cap being also provided at the bottom end thereof with an annular recess for receiving the proximate end of said insulator body.

ROBERT S. BACH.
